UNITED STATES PATENT OFFICE.

WILLIAM RICHARD WHITE, OF BLOOMINGTON, ILLINOIS.

GATE.

SPECIFICATION forming part of Letters Patent No. 614,682, dated November 22, 1898.

Application filed May 11, 1898. Serial No. 680,371. (No model.)

To all whom it may concern:

Be it known that I, WILLIAM RICHARD WHITE, a citizen of the United States, residing at Bloomington, in the county of McLean 5 and State of Illinois, have invented certain new and useful Improvements in Gates, of which the following is a specification.

This invention relates to certain new and useful improvements in swinging gates; and 10 it consists, substantially, in such features of construction, arrangement, and combinations of parts as will hereinafter be more particularly described.

The movable latch-bar of the gate of my 15 present improvement is normally in an advanced or projected position when the gate is closed, this position of the latch-bar, however, being the same as is set forth in some patents already granted to me on this subject.

20 I have heretofore employed operating devices for the latch-bar which by their arrangement and construction projected more or less from the side of the gate, and as a support and protector for said devices I have also 25 usually employed some form of laterally-projecting frame on the side of the gate, and while my former gates have given satisfactory results it is desirable in some instances to have as little weight as possible at the hinged 30 end of the gate as well as to dispense with all laterally-projecting parts or outside constructions. In other words, it has been found desirable that the latch-bar-operating devices shall lie as close to and work as nearly as 35 possible in line with the side of the gate, and it will be understood that this is the principal object of the present invention, although it also has other objects in view, as will herein- 40 after more fully appear when taken in connection with the accompanying drawings, in which—

Figure 1 is a perspective view of a swinging gate embodying my improvements, the gate being shown in its closed position. Fig. 45 2 is a view in perspective showing my improved adjustable gate-support, and Fig. 3 is a view in perspective of the support detached.

50 My present invention may be carried into effect in different ways; but preferably I employ substantially the embodiment herein

shown, wherein a lever is used for projecting the latch-bar. The said lever is preferably a spring-lever, with its plane of movement or action in line with the side of the gate and directly adjacent thereto. By this arrangement 55 all projecting portions from the side of the gate are dispensed with, and the gate is thereby rendered considerably lighter at the hinged end.

The connecting-bar from the operating hand-levers is preferably connected directly with the latch-bar near to the inner end thereof, or, if desired, the connection may be 60 made immediately at the end.

I shall hereinafter make specific mention 65 of my improved adjustable support for the gate on its hinges.

In the accompanying drawings, 1 represents the supporting-post for the gate 2, which latter may be either of wood or metal and may be constructed in any suitable way. Opposite to said post, on the other side of the gate-opening or roadway, is another post 3, against which the free end of the gate rests 70 when the gate is closed, the said post having projecting therefrom a catch or keeper 4, having a shoulder 5, which engages the outer end of the latch-bar. On the same side of the roadway as the post 1 and in alignment therewith are the posts 6 and 7, a cross-brace 9 uniting these three posts, while post 6 is provided with a catch or keeper 4' to engage the latch-bar when the gate is in its open position.

The operating-levers 10 10 are respectively 85 fulcrumed to the post 6 and to a support or frame 11 on the post 1, and as distinguished from the arrangement of similar levers in my former patents they are required by the construction shown in Fig. 1 to be pulled down 90 at their outer ends to open the gate and to be pushed upward to close the gate. This results from the fact that the connecting-bar 11 between the hand-levers and gate does not describe as great a sweep as in the former 95 constructions referred to, and consequently the hand-levers are caused to remain practically at a horizontal position when the gate is open instead of being carried downward at their inner ends by their own weight, as before. 100 An advantage results from this in the fact that but a limited movement of the hand-le-

vers is necessary and the gate is carried positively back and forth in the act of opening and closing the same.

The inner ends of the operating-levers 10 10 5 are loosely connected together, so that upon the application of force to either lever they both move together as usual, and in order to properly guide the inner ends of the levers in their up and down movements I provide one 10 10 of them with an elongated staple 8, firmly secured thereto and extending around the post 7 and free to slide thereon and permit the requisite sweep of the levers in the operation of the gate.

15 The gate 2, as herein shown, is constructed of a number of flat bars united at suitable distances apart by means of the duplicate vertical strips 12, between which latter the latch-bar 13 is guided in its longitudinal movements, the said latch-bar being provided with a loop 14 at its outer end to engage the shoulders of the catch-plates 4 and 4' on posts 3 and 6.

As shown in Fig. 1, the connecting-bar 11, 25 that movably connects with one of the hand-levers, is in movable connection with the latch-bar 13, near the inner end of the latter, as shown at 16; but in some instances this connection may be made directly at the end of 30 the bar, an eye, loop, or other similar fastening 16^a being provided for the purpose.

Projecting from the side of the gate above the latch-bar is a pin 18, (or it could be an eye,) and on the side of the topmost bar of 35 the gate is secured a strip 19, the outer end of which is about in vertical alinement with the pin 18. A spring-lever 20, secured at its upper end to the end of the strip 19 and extending downward close to the side of the 40 gate, is mounted on the pin 18 under tension and has its lower end bent laterally and inserted in an opening 17 in the latch-bar, the end of the lever being prevented in any suitable way from slipping out. This spring-lever could be secured to the end of the strip 45 19 either by solder, a screw or rivet, or in any suitable manner, and from the construction and arrangement shown it will be seen that the tendency of the lower end of the said lever is to maintain the latch-bar in a slightly- 50 advanced position to keep the gate locked while closed. Immaterial changes could be resorted to in this general arrangement and still be within the scope of the invention.

55 It will be seen that when one of the hand operating-levers is depressed the latch-bar will be drawn inwardly against the tension of the spring-lever 20 and the gate will be released, whereupon the strain will be imparted 60 directly to the gate and the latter will be carried to its extreme open position and there become engaged or locked. To return the gate to its closed position, substantially the same operation takes place by pushing up- 65 wardly on one of the hand-levers.

In the construction shown the weight of the

inner ends of the hand-levers maintains the latch-bar in its locked position, and the force of the spring 20 also constantly tends to press the latch-bar forward. The gate is thus kept 70 securely locked in both positions, while at the same time it requires but comparatively little strength to release the latch-bar on manipulation of the hand-levers.

I have also devised an improved form of 75 adjustable support, which is preferably employed in connection with my improved gate, by which to sustain the gate at different vertical heights on its hinges, and while this support could also be changed in different respects as regards its particular shape I prefer the construction I am about to describe. Thus the supporting-post 1 for the gate is provided with the loop or staple hinges 40 of ordinary form, and between said hinges the post 80 85 is provided with a number of perforations 41, arranged in vertical alinement.

The vertically-adjustable support itself is designated at 42 and comprises an arm 43, having at its lower end two fingers 44, extending in opposite directions to each other, one being for the purpose of entering the perforations 41 in post 1 and the other serving as a handle to manipulate it properly in raising or lowering the gate and fixing or setting 90 the support in place. The upper end of said support has two offset portions 50 and 51, one of which, preferably the upper one 51, is simply perforated for the passage of the hinge, while the lower one 50 is bifurcated at 52. 100 This construction facilitates placing the support upon the hinge while assembling the parts and at the same time provides for a ready adjustment of the support on the post when it is desired to change the elevation of 105 the gate. Said support could be cast or constructed in various ways; but preferably I form the same in two parts *a* and *b* and rivet or otherwise secure them together at *c d*. The construction shown furnishes great 110 strength and is easily and cheaply made.

It will be understood that while arranging the gate-support in position upon the loop or staple hinge the hinge portion *e* on the gate is so fitted upon the hinge as to come between 115 the offset portions at the upper end of the support, and consequently when the support is raised or lowered the gate will be carried with it.

Without limiting myself to the precise details of construction and arrangement shown and described, what I claim is—

1. In a swinging gate, the combination of a movable latch-bar, operating hand-levers for the gate, a projection on the side of the 125 gate above the latch-bar, a spring-lever disposed in vertical position and secured at its upper end to the gate, and being in movable connection at its lower end with the latch-bar, said lever bearing against the projection 130 and tending to maintain the latch-bar in an advanced position, and a connecting-bar be-

tween said latch-bar and the inner end of one of the hand operating-levers, substantially as described.

2. In a swinging gate, the combination with the gate, its supporting-post having the perforations, and the hinges, of the adjustable support having the offset portions fitting upon one of the hinges and constructed with fingers extending in opposite directions, one of said

10 fingers adapted to enter said perforations, while the other constitutes a handle, substantially as described.

3. In a swinging gate, the combination with the gate, its supporting-post having a series 15 of perforations, and the hinges, of the adjustable support having offset portions at its upper end, one of which portions is perforated and the other bifurcated to engage one of the hinges as set forth, the lower end of the support being provided with a lateral finger 20 adapted to enter the perforation in said post, substantially as described.

4. In a vertically-adjustable swinging gate, the adjustable support for the gate constructed of two parts secured together and having 25 the offset projections at its upper end, one being perforated to receive the hinge and the other being bifurcated to embrace the hinge, the said support having at its lower end the fingers projecting in opposite directions to 30 each other, substantially as described.

5. The combination of the posts, the gate, the pivoted operating-levers, the connections between the gate and levers and a staple on one of said levers passing around one of the 35 posts, substantially as set forth.

In testimony whereof I have signed my name to this specification in the presence of two subscribing witnesses.

WILLIAM RICHARD WHITE.
